UNITED STATES PATENT OFFICE.

JOHN ELLIS, OF PITTSBURGH, PENNSYLVANIA.

GAS-CONTROLLING MECHANISM FOR INSTANTANEOUS WATER-HEATERS.

1,053,369.

Specification of Letters Patent.

Patented Feb. 18, 1913.

Application filed March 20, 1912. Serial No. 684,960.

To all whom it may concern:

Be it known that I, JOHN ELLIS, a citizen of the United States, residing at Pittsburgh, in the county of Allegheny and State of Pennsylvania, have invented a new and useful Improvement in Gas-Controlling Mechanism for Instantaneous Water-Heaters, of which improvement the following is a specification.

10 My invention relates to automatic instantaneous water heaters, relating in particular to the mechanism intermediate the thermostat and gas valve controlled thereby.

15 The object of my invention is to improve the above mechanism and provide means to prevent accidental displacement of and tampering with the necessary delicately adjusted parts for transmitting movement to the gas valve from the thermostat rod, by 20 entirely inclosing the working parts within a chamber and providing the chamber with means for adjusting the parts therein.

25 A further object is to dispense with stuffing boxes as is usually employed in connection with the gas valve.

With the above objects in view, the invention consists in certain novel features of construction, and in certain parts, improvements, and combinations of parts as will be hereinafter more fully described and 30 pointed out in the appended claims.

One embodiment of the invention is illustrated in the accompanying drawings, forming a part of this specification, each detail part of the structure being given and referred to by its individual reference numeral throughout the several views wherein they appear, said views representing the following:

40 Figure 1 is a longitudinal or side sectional elevation through the chamber disclosing the working parts therein. Fig. 2 is a plan, on the line X—X of Fig. 1, of the lower section of the chamber. Fig. 3 is an end elevation of the lower section. Fig. 4 is a side elevation showing the application of the chamber to the other parts of the heater, said parts being shown in dotted lines.

50 In detail, the improvement consists of a casing formed of the two parts 1 and 2, respectively, each containing a chamber, the upper part having arranged therein a disk valve 3 held upon its seat about the communicating opening 4, between the chambers, by a spiral spring 5 interposed between

the screw cap 6 and valve and surrounding the downwardly projected guide 6' of the cap and the valve stem engaging therein, said upper chamber casing portion having 60 an opening formed therethrough within the extended and threaded boss 1' by which that portion of the chamber is connected to the gas cock in the line from the heater burner. The lower chamber casing 2 is connected by 65 its threaded boss 2' to the water jacket and the thermostat tube, therein inclosing the thermostat actuated rod 7, which rod projects into the chamber, and is further connected, by its open boss 2'', to and communicates with the pipe leading from and connected with the water pressure actuated valve in the gas line.

70 Within the lower chamber is arranged the mechanism for communicating movement from the thermostat rod to the gas valve in the upper chamber, comprising the horizontally disposed thrust pin 8 having a vertically disposed portion 8' at its rear engaging with the end of the thermostat rod, and 75 a base guide portion 8'' where it rests upon the lower wall of the chamber, said thrust pin terminating in a point. A vertically disposed lever rest 9 is arranged within the rear of the chamber, is forked at its upper 80 end and provided at its lower rear portion with a transverse rib 9' at a point below the axial line of the thrust pin, said lever rest being further provided with a transversely disposed knife-edge fulcrum rib 9'', in 85 front, at a point above the axial line of the thrust pin. A vertically disposed primary lever 10 is interposed between the thrust pin and lever rest, with the point of the pin 90 engaging the rest in the small conical opening 10' in the face thereof, the upper end of said lever being rounded and extends up between the forked portion of the lever rest. A horizontally disposed secondary lever engages at its forward end with a downwardly 95 projected portion formed upon the underside of the disk valve and is provided at its rear end, where it extends through the forked portion of the lever rest, with laterally disposed knife-edged fulcrum points 100 engaging within the grooves at the rear of the forked portion of the lever rest, and is further provided with a downwardly extended portion 11'' in engagement with the upper end of the primary lever.

105 Within the rear wall of the lower chamber, near the base, is fitted a screw-plug 12

which engages the transverse rib portion 9 of the lever rest, serving to adjust and take up the slack between the said rest, the primary lever, the thrust-pin and the 5 thermostat rod, a jam nut 13 being arranged on the screw-plug for securing it in adjusted position. A small set screw 14 is also arranged within the rear wall of the chamber, forming an abutment for and serving 10 to regulate the temperature by adjusting the upper end of the lever rest and lever mechanism, which screw is provided with a jam nut 15 to secure it in adjusted position.

15 Assuming that the water in the heater has reached a sufficiently high temperature that the gas valve has been seated by the spring 5, as shown in Fig. 1, cutting off the gas supply, then upon cooling of the water in 20 the heater the operation of opening the valve would be as follows: The thermostat tube in contracting, pushes the rod 7 to tube in contracting, pushes the rod 7 toward the chamber, causing a like movement of the thrust pin 8 which acts upon the 25 primary lever 10, the upper end of said lever acting upon the secondary lever causes its free end to elevate and raise the gas valve from its seat, thus permitting the gas to flow through the chamber, the spring 5 30 returning the gas valve to its seat when the temperature of the water has again sufficiently increased.

By providing a chamber within the gas line, and inclosing the gas valve and mechanism therein, no stuffing box is required for the valve stem, and the parts for operating the valve from the thermostat rod not requiring connection with one another, and being loosely disposed within the chamber 40 are easily and quickly assembled, cannot become displaced or disarranged and readily adjusted from the exterior when desired.

Having shown and described my invention, I claim:

45 1. In an instantaneous water heater, the combination of a chamber in the gas line, a thermostat tube connected thereto, a thermostat rod projecting from said tube into said chamber, a gas controlling valve in

said chamber, a seating spring engaging 50 said valve, a lever rest loosely seated in said chamber, a primary lever fulcrumed upon said rest and adapted to be operated by the thermostat rod, and a secondary valve-raising lever fulcrum upon said rest 55 and operated by said primary lever.

2. In an instantaneous water heater, the combination of a chamber in the gas line, a thermostat tube connected thereto, a thermostat rod projecting from said tube into 60 said chamber, a gas controlling valve in said chamber, a seating spring engaging said valve, a thrust pin operated by said thermostat rod, a primary lever operated by said thrust pin, a lever rest loosely seated 65 in said chamber and having said primary lever fulcrumed thereon, a secondary valve raising lever also fulcrumed upon said rest and operated by said primary lever, and screws extending into said chamber engaging 70 said rest for adjusting the temperature and taking up the slack between the levers, the thrust pin and thermostat rod.

3. In an instantaneous water heater, the combination of a chamber in the gas line, 75 a thermostat tube connected thereto, a thermostat rod projecting from said tube into said chamber, a gas-controlling valve in said chamber, a spring for seating the same, a thrust pin operated by said thermostat 80 rod, a primary lever operated by said thrust pin, a lever rest loosely seated in said chamber and having said primary lever fulcrumed thereon, a secondary valve-raising 85 lever also fulcrumed upon said rest and operated by said primary lever, and screws extending into said chamber engaging said rest for adjusting the temperature and taking 90 up the slack between the levers, the thrust pin and thermostat rod.

In testimony whereof, I have hereunto signed my name in the presence of two subscribing witnesses.

JOHN ELLIS.
